HERBERT F. BEEBE, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

BATTERY HAND LAMP.

Application filed April 25, 1927. Serial No. 186,398.

This invention relates to battery hand lamps of the type including a casing for the battery, a lamp bulb, a switch mechanism for controlling the electric current through the battery and the bulb, and a bottom end cap for closing the bottom end of the casing and holding the battery in proper position within the casing. The present invention more particularly concerns supporting means carried by the bottom end cap of a hand lamp of the type described, whereby such lamp may be conveniently supported from a hook, peg or other support.

It has been found desirable and convenient to provide hand lamps of the type described with suitable means, such as a hook or ring, for use in hanging the lamp vertically from a hook or peg, the lamp casing extending downwardly from such support. A supporting means of this type should be so mounted that it does not in any way interfere with the operation and handling of the lamp, while at the same time it is readily accessible when it is desired to hang the lamp on a support.

With the above and other considerations in mind, it is proposed in accordance with the present invention to provide a battery hand lamp having an improved form of supporting means mounted on the bottom end cap thereof, and, more specifically, it is proposed to provide a supporting means in the form of a hook which is so mounted and arranged that it may be folded down into a depression in the bottom end cap or the bottom end of the casing of the lamp when not in use, whereby no part of the supporting hook is exposed to accidental contact with the hands or clothing of the operator or with other objects.

It is a further object of the invention to provide a supporting hook of the type described which has a swivel connection with the end cap, in order that this hook may be turned to various positions relative to the hand lamp when in use.

Other specific objects, advantages and characteristic features of the invention will become apparent as the description thereof progresses.

In describing the invention in detail, reference will be made to the accompanying drawings, in which:

Figure 1 is a sectional side view of a por-

tion of the casing of a hand lamp together with the bottom end cap, embodying the supporting means of the present invention;

Fig. 2 is a view of the lower end of the bottom end cap, showing the supporting hook;

Fig. 3 is a sectional view similar to Fig. 1, showing the lamp supporting hook open and in use;

Fig. 4 is a sectional view of the bottom end cap and supporting hook, taken along the line 4-4 of Fig. 2 and viewed in the direction of the arrows; and

Fig. 5 is a view of the lower end of the bottom end cap showing a modified form of the lamp supporting hook.

In the embodiment of the invention illustrated, the lamp comprises a metallic battery casing 1, carrying a battery 2 composed of one or more dry cells arranged end to end in series connection in the usual and well known manner. A bottom end cap 3 closes the lower end of the casing 1, being secured thereto by a screw threaded engagement therewith as shown, or by other suitable means. The electrical circuit between the casing 1 and the base of the lowest cell of the battery 2 is completed through a spiral spring 4. The lowest coil spring 4 is slightly larger in diameter than the internal diameter of the end cap 3, and this coil is slightly compressed and forced within the cap where it expands and grips the inner cylindrical wall of the cap, thereby effecting a firm connection between the cap and the spring.

Referring now more particularly to the hand lamp supporting hook comprising an important feature of the present invention, the bottom face of the end cap 3 is provided with a depression or recessed portion 6 of general diamond shape as shown in Fig. 2. This depression 6 is preferably pressed or stamped in the sheet metal of which the cap 3 is formed, and is so disposed that the surface of the bottom of the cap extends around this depression in an unbroken plane. A small pocket or extension 7 is formed at one corner of the depression 6, this pocket being covered by an overhanging ledge or extension 8, as shown in Figs. 1 and 2. A stud T is rotatably journaled in a circular opening 9 in the depression 6 at a point directly opposite the pocket

7. The stud T may take any suitable form, but in the preferred embodiment shown comprises a piece of sheet metal having a circular flange 10 and a hollow cylindrical portion 11. The cylindrical portion 11 of the stud T is provided with alined circular openings in the cylindrical walls thereof, and one end 12 of a hook H is journalled in these openings as clearly shown. The end 12 of the hook H may be retained within the openings in the stud T in any suitable manner, and in the embodiment shown a circular groove or depression 14 is provided in the end 12 and the lower end of the stud T is pressed inwardly to form a ridge 15 for engaging the groove 14, and thus retaining the end 12 within the stud. The stud T is thus rotatably secured within the opening 9 by means of the engagement of the flange 10 with the inner surface of the depression 6, and the engagement of the end 12 of the hook H with the outer face of this depression.

The hook H is formed of a suitable resilient material such as spring steel preferably bent to the form shown in Fig. 2, having a bend or corner 16 near the free end thereof. The hook H is of a size such that when pressed into the depression 6 it is slightly compressed, the corner 16 snapping under the ledge 8 and into the pocket 7, thereby retaining the hook H within the depression 6 when not in use.

When it is desired to employ the hook H for supporting the lamp, the hook may be easily and quickly extracted from the depression 6 by inserting the thumb or finger nail beneath the portion 17 thereof and prying the corner 16 out of the pocket 7. During this operation, the hook H turns about the axis of the lower end portion 12 which is journalled in the stud T, the free end 18 of the hook bearing against the face of the depression 6, and the operator thereby obtaining a mechanical advantage, similar to a camming action, in prying the corner 16 past the ledge 8.

In Fig. 5, a slightly modified form of supporting hook and retaining depression has been shown. In this modification, the depression 20 has an extension or pocket 21 in the wall thereof opposite the stud T, and two ledges or extensions 22 and 23 are formed on the walls of the depression adjacent each side of this pocket 21 as shown. The hook H' of this modification is of substantially S shape, and the end portion 24 thereof may be retained within the transverse opening in the stud T by any suitable means, as by flattening or enlarging the extreme end 25 thereof as shown. The hook H' is formed of resilient metal and is sprung beneath ledges 22 and 23 and thus retained within the depression 20 when not in use. To extract the hook H', the thumb or finger

nail is inserted beneath the hook at the pocket 21, and the hook is thus pried out from under the ledges 22 and 23.

It should be particularly noted that when the hook H is snapped into the depression 6, all parts of the hook are entirely within the plane of the bottom face of the end cap 3 and the hook is thus completely protected against accidental displacement by contact with the clothing or hands of the operator or with other objects. This complete protection of the hook is a highly important feature. If the hook H were at any point exposed in such a manner that it could be accidentally opened, this hook might catch on objects and the lamp might be drawn from the operator's hand or such opening of the hook might in various other ways inconvenience the operator in handling the lamp. It should be further noted that with the hook H folded down within the recess 6, the exterior surface of the bottom end cap 3 is unbroken when viewed from the side of the lamp, and in this manner, a lamp of pleasing appearance is provided. With the hook H folded into the depression 6, an unbroken plane surface is presented around the rim of the cap 3, as shown in Figs. 1 and 4, and the lamp may be placed on end on a table or other plane surface if desired.

It is often desired to hang a hand lamp on an available object in such a manner that the light beam therefrom is projected downwardly to some desired point. With the folding hook of the present invention, this may be conveniently accomplished, the hook H being pried out of the depression of the end cap and swung in any desired position relative to the lamp casing to engage any supporting object that may be available. The lamp may be conveniently hung up in this manner when not in use. It should be noted that the preferred form of the hook, as shown in Figs. 1 through 4, is particularly adaptable for supporting the lamp from a variety of differently shaped objects. For example, this hook H may be employed to support the lamp from a nail or peg as shown in Fig. 3, or the hook may be swung out over the edge of the lamp casing and passed over the edge of a vertical plane surface such as a partition wall or lath, or the belt or other part of the clothing of the operator.

It is to be understood that the present invention is not limited to the particular embodiment illustrated and described, but includes such modifications thereof as fall within the scope of the appended claims. For example, the hook may be secured to the end cap without the use of the swivel connection disclosed, and various means other than those shown may be employed to obtain a universal connection between the hook and the cap.

I claim:

1. In a hand lamp, a battery casing, a central depression in one end face of said casing, a member rotatably secured in an opening 5 within said depression, a hook hingedly secured to said member, and means for releasably retaining said hook in said depression.
2. In a hand lamp, the combination of a 10 battery casing, a cap secured to one end of said casing, a central depression in the end of said cap, a member rotatably secured within said depression near one side thereof, a hook hingedly secured to said member, and 15 means on the wall of said depression opposite said member for releasably retaining said hook within said depression.
3. In a hand lamp, the combination of a 20 battery casing, a cap secured to one end of said casing, a central depression in the end of said cap, a stud rotatably secured within said depression near one side thereof, a lamp supporting member hingedly secured to said stud, and means for releasably retaining said 25 lamp supporting member within said depression when not in use.
4. In a hand lamp, the combination of a 30 battery casing, a cap secured to one end of said casing, a central depression in the end of said cap, a stud rotatably secured within said depression near one side thereof, a resilient hook hingedly secured to said stud, and a ledge on the wall of said depression 35 opposite said stud for engaging said hook when it is folded within said depression.
5. In a hand lamp, the combination of a 40 battery casing, a cap secured to one end of said casing, a central depression in the end of said cap, a stud rotatably journaled in an opening in said depression, said stud having 45 a transverse opening therethrough, a hook having an end journaled in said transverse opening in said stud, inter-engaging means on said stud and the end of said hook for retaining said end within said transverse opening and means for releasably retaining said hook within said depression.
6. In a hand lamp, the combination of a 50 battery casing, a cap secured to one end of said casing, a central depression in the end of said cap, a stud rotatably secured within said depression near one side thereof, a ledge on the wall of said depression opposite said stud, a resilient hook hingedly secured to said stud, and a bend in said hook adjacent 55 the free end thereof forming a corner for engagement with said ledge whereby said hook may be retained within said depression.
7. In a hand lamp, the combination of a 60 battery casing, a cap secured to one end of said casing, a central depression in the end of said cap, a stud rotatably secured within said depression near one side thereof, a pocket in the wall of said depression opposite said stud, a resilient hook having a 65 hinge connection with said stud, the free end of said hook terminating at a point substantially aligned with the axis of said hinge connection and a corner of said hook near the free end thereof for engaging said 70 pocket and retaining said hook within said depression.

In testimony whereof I affix my signature.
HERBERT F. BEEBE.
